UNITED STATES PATENT OFFICE.

DAVID P. BARRY, OF NEW YORK, N. Y.

DESIGN FOR A PIN OR BUTTON HEAD.

No. 38,965.

Specification for Design.

Patented Dec. 31, 1907.

Application filed September 6, 1907. Serial No. 391,731. Term of patent 7 years.

To all whom it may concern:

Be it known that I, DAVID P. BARRY, a citizen of the United States, and a resident of the city of New York, borough of Brooklyn, in the county of Kings and State of New York, have invented a new, original, and ornamental Design for Pin or Button Heads, reference being had to the accompanying drawing.

The figure is a perspective view of a pin or button head showing my new design.

I claim:

An ornamental design for a pin or button head as shown.

DAVID P. BARRY
